CONTROL CONSOLE FOR AUTOMATIC WASHING MACHINE

Roger L. Dillon, Cottage Grove, Spencer B. Larson,
South St. Paul, and Marcus I. Nystuen, St. Paul, Minn.,
assignors to Economics Laboratory, Inc., St. Paul, Minn.

Filed Mar. 12, 1974, Ser. No. 450,358

Term of patent 14 years

Int. Cl. D15—05

U.S. Cl. D49—1 R

FIG. 1

FIG. 2

FIG. 3

FIG. 4

FIG. 5

FIG. 1 is a perspective view of a control console for automatic washing machine, showing our new design;

FIG. 2 is a top plan view;

FIG. 3 is a front elevational view;

FIG. 4 is a left side elevational view; and

FIG. 5 is a right side elevational view.

We claim:

The ornamental design for a control console for automatic washing machine, as shown and described.
